ABSTRACT: An extremely compact electronic cartridge for delaying the delivery of a firing pulse to a squib which initiates a main charge. The delay provided by the circuit is maintained constant with temperature variations by using a thermistor in the circuit, and the original firing pulse is provided by a thermal battery.

ELECTRONIC DELAY CARTRIDGE

GOVERNMENT INTEREST IN THE INVENTION

The invention described herein may be manufactured and used by or for the Government of the United States of America for governmental purposes without the payment of any royalties thereon or therefor.

BACKGROUND OF THE INVENTION

1. Field of the Invention

This invention relates generally to devices for delaying the initiation of an explosive charge and more particularly to an electronic delaying device having substantially constant delay time with temperature change.

2. Description of the Prior Art

In many applications, such as escape systems, it is desirable to have a delay period between the time initiation action is started and the time the initiation of the main explosive occurs. For such applications, the prior art has generally used pyrotechnic delay cartridges in which the original initiation action ignited a percussion primer which in turn initiated a pyrotechnic delay column. The pyrotechnic delay column was made of slowly burning explosive which would delay the speed with which the detonation would reach and initiate the main charge. A disadvantage of a pyrotechnic delay cartridge is that the pyrotechnic mix in the delay column must be mixed and pressed under carefully controlled conditions in order to maintain constancy of delay time. Regardless of the care taken in preparing pyrotechnic delay cartridges, delay time variations in excess of ± 25 percent are common, and delays over five seconds are very difficult to produce.

Electronic delay cartridges have also been proposed in the prior art however these have been bulky and the delay time would vary with temperature changes. Also, the power sources used were normally ordinary batteries whose power would decay with time even if not used.

SUMMARY OF THE INVENTION

The disadvantages of the prior art have been overcome by providing an extremely compact electronic delay cartridge activated by a thermal battery and having a thermistor in the delay circuit to maintain the delay time constant with temperature variations.

It is an object of this invention to provide a delayed initiation device to electronically delay the initiation of a charge after starting the initiation process.

It is another object of this invention to provide such a delayed initiation device whose delay time is minimally affected by temperature variations.

It is still another object of this invention to provide such a delayed initiation device which is extremely compact.

A further object of the invention is to provide an electronic delayed initiation device which can be activated by the application of heat.

It is another object of this invention to provide an electronic delayed initiation device which can be reliably activated long after it has been installed in an explosive system.

Other objects, advantages and novel features of the invention will become apparent from the following detailed description of the invention when considered in conjunction with the accompanying drawings.

BRIEF DESCRIPTION OF THE DRAWINGS

FIG. 1 shows the basic construction of an electronic delay cartridge according to applicants' invention;

FIG. 2 shows applicants' delay cartridge when the components are fitted into a casing the size of a 38 caliber shell casing, and the details of the squib initiation system;

FIG. 3 shows the connection between the thermal battery and the printed delay circuit according to applicants' invention; and

FIG. 4 shows the electronic delay circuit of applicants' device.

DESCRIPTION OF THE PREFERRED EMBODIMENTS

FIG. 1 shows the basic construction of the electronic delay cartridge generally designated by reference numeral 11, comprising a casing 12, having therein a thermal battery 14, an electronic delay circuit 15, a squib initiation system 16, and a main charge 18.

Thermal batteries are well known in the art and any known thermal battery could be used. Activation of the thermal battery can be accomplished in a number of ways for example by means of a percussion primer or by means of an electric match. Upon activation the thermal battery provides a pulse of electricity to the delay circuit. The delay circuit delays delivery of this pulse to the squib a predetermined amount of time, which is set by the circuit parameters. When the pulse reaches the squib, the squib is heated and ignites the main charge.

FIG. 2 shows in greater detail certain portions of a delay cartridge such as that shown in FIG. 1. A casing 19 the size of a 38 caliber cartridge contains a thermal battery 20 and an electronic delay circuit 21. The initiation assembly 22 is of conventional design and contains a bridge wire squib 26 surrounded by lead styphnate 25. Around the bridge wire and lead styphnate is an ignition mixture 24. The ignition mixture 24 is separated from main charge 28 by spacer 17 having an aperture therethrough to allow detonation of the main charge by the ignition mixture. Upon delivery of the electric pulse by the delay circuit to bridge wire 26 the lead styphnate is ignited thereby igniting the ignition mix 24. This in turn ignites main charge 28.

The cartridge has been constructed to be of minimum size. As can be seen in FIG. 3 the first step in construction of the delay cartridge is to electrically connect the printed delay circuit board 35 to a thermal battery 20. Leads 32 and 34 extend through aligned apertures 37 and 39, and 33 and 38 in the printed circuit board and the thermal battery to connect the battery to the printed circuit. The printed circuit board is then placed adjacent the end of the thermal battery 20 and the assembly is then inserted into casing 19 into abutment with shoulder 23. Member 27, containing the igniter assembly and the bridge wire and ignition mix is then inserted into the cartridge, and leads from the bridge wire are plugged into the printed circuit board. Main charge 28 is then packed into member 27 and enclosure plate 29 is placed over the end of the cartridge. The end of the cartridge 31 is then crimped over an O-ring 30 to retain the entire assembly within casing 19.

FIG. 4 shows the novel delay circuit of the invention. A conventional thermal battery 20 is used to provide power to the circuit. A thermal battery is one which is normally inert but upon application of heat is activated to provide a pulse of electricity to the circuit. Normally this is done by melting of an electrolyte which then flows into the battery to activate it. Since the electrolyte is not normally in the battery, a thermal battery never deteriorates from setting inactive. This means that it is reliable to provide power for initiation of an escape system or the like long after it has been installed, whereas a conventional battery could very well be discharged and useless. Upon activation of battery 20, capacitor 37 begins being charged through resistor 36. Unijunction transistor 38 is normally reverse biased, but after capacitor 37 has become sufficiently charged, the unijunction transistor becomes forward biased, thereby effectively shorting capacitor 37 across resistor 39 and the gate to cathode region of a silicon controlled rectifier 42. This pulse applied to the gate of the silicon controlled rectifier turns it "on" thus applying power to the bridge wire 26.

To control the effect of temperature variations on the time delay circuit, a thermistor 41 was placed in parallel with resistor 40 creating an equivalent resistance which varies with temperature. Variations of the resistance of the thermistor 41 with temperature will maintain the time delay between activation of the thermal battery and the supplying of power to bridge wire 26 essentially constant with temperature. The resistance of resistor 40 has an effect on the voltage to which

capacitor 37 must build to forward bias unijunction transistor 38. By placing thermistor 41 in parallel with resistor 40, a temperature variable biasing resistance has been provided which compensates for temperature induced variations in other circuit parameters to maintain substantially constant the time necessary for capacitor 37 to charge to the level required to forward bias unijunction transistor 38. Experimentation has shown that the time delay period varies less than ± 3 percent between the temperatures of -60° and +160° F.

Thus it can be seen that an extremely compact electronic delay cartridge has been produced which provides a delay time which is substantially constant over a wide range of temperatures.

Obviously, many modifications are possible in view of the above teachings. For example, thyratron circuits could be employed instead of solid a circuitry. Also, this delay circuit could be used in environments other than explosive initiation. It would be useful anytime a temperature independent delay time is desired.

What is claimed is:

1. Means for delayed initiation of an explosive charge comprising:

an electronic delay circuit including means for maintaining time delay constant with temperature variation;
a thermal battery actuatable to provide power to said delay circuit; and
means connected to said thermal battery by said delay circuit to initiate said explosive charge.

2. The device of claim 1 wherein said maintaining means comprises a thermistor.

3. The device of claim 1 wherein said electronic delay circuit comprises:

switch means;
means normally biasing said switch means open;
a capacitor which is charged by said thermal battery to overcome the bias on and close said switch means, and to discharge through said switch means to activate said initiation means;
said biasing means including the means for maintaining time delay constant with temperature variation.

4. The device of claim 3 wherein said maintaining means comprises a thermistor.

5. The device of claim 3 wherein said switch means comprises a unijunction transistor and said biasing means comprises resistors connected thereto, said maintaining means comprising a thermistor in parallel with one of said resistors.

6. The device of claim 5 further including a silicon controlled rectifier between said unijunction transistor and said initiating means normally preventing current flow from said unijunction transistor to said initiating means, said silicon controlled rectifier allowing such current flow in response to the discharge of said capacitor through said unijunction transistor.

7. The device of claim 1, wherein said electronic delay circuit comprises:

a first resistor and a capacitor connected in series across

said thermal battery;

a unijunction transistor having its emitter connected between said resistor and capacitor;
a first base region of said unijunction transistor being connected through a second resistor across said capacitor;
a silicon controlled rectifier having its gate connected to said first base region and its cathode in parallel with said second resistor, the anode of said silicon controlled rectifier being connected to said initiation means; and
a thermistor connecting said initiation means to a second base region of said unijunction transistor, said second base region and thermistor being in parallel with said first resistor.

8. The device of claim 7 wherein said initiation means comprises a fourth resistor.

9. An electronic delay circuit comprising:

a power source;
switch means;
means normally biasing said switch means open;
a capacitor which is charged by said power source to overcome the bias on and close said switch means and to discharge through said switch means; and
said biasing means including thermistor means to maintain the time necessary to overcome the bias on said switch means substantially constant with temperature variations.

10. The circuit of claim 9 wherein said switch comprises a unijunction transistor and said biasing means comprises resistors connected thereto, said thermistor maintaining means comprising a thermistor in parallel with one of said resistors.

11. The circuit of claim 10 further including a silicon controlled rectifier between said unijunction transistor and said initiating means normally preventing current flow from said unijunction transistor to said initiation means, said silicon controlled rectifier allowing such current flow in response to the discharge of said capacitor through said unijunction transistor.

12. An electronic delay circuit comprising:

a power source;
a first resistor and a capacitor connected in series across said power source;
a unijunction transistor having its emitter connected between said resistor and capacitor;
a first base region of said unijunction transistor being connected through a second resistor across said capacitor;
a silicon controlled rectifier having its gate connected to said first base region and its cathode in parallel with said second resistor;
an ultimate current delivery portion, said current delivery portion being connected to the anode of said silicon controlled rectifier; and
a thermistor connecting said current delivery portion to a second base region of said unijunction transistor, said second base region and thermistor being in parallel with said first resistor.

13. The circuit of claim 12 wherein said ultimate current delivery portion comprises a fourth resistor.
